CLAIM

The ornamental design for a mobile phone, as shown and described.

DESCRIPTION

FIG. 1 is a front view of a first embodiment of a mobile phone showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a front view of a second embodiment of a mobile phone showing our new design;

FIG. 8 is a rear view thereof;

FIG. 9 is a front view of a third embodiment of a mobile phone showing our new design;

FIG. 10 is a rear view thereof;

FIG. 11 is a front view of a fourth embodiment of a mobile phone showing our new design;

FIG. 12 is a rear view thereof;

FIG. 13 is a front view of a fifth embodiment of a mobile phone showing our new design;

FIG. 14 is a rear view thereof;

FIG. 15 is a front view of a sixth embodiment of a mobile phone showing our new design; and,

FIG. 16 is a rear view thereof.

The left side, right side, top, and bottom views of the second through sixth embodiments are identical to the corresponding views of the first embodiment with the exception of the location of the protruding structure on the plan views as it relates to the rear view.
